(57) **CLAIM**

The ornamental design for a water filter housing, as shown and described.

DESCRIPTION

FIG. 1 is a top, side and front perspective view of a water filter housing showing my new design;

FIG. 2 is a bottom, side and rear perspective view thereof;

FIG. 3 is a front elevation view thereof;

FIG. 4 is a rear elevation view thereof;

FIG. 5 is a right side elevation view, the left side elevation being a mirror image thereof;

FIG. 6 is a top plan view thereof; and,

FIG. 7 is a bottom plan view thereof.

The broken line showing in FIGS. 1 and 3 is included for the purpose of illustrating and forms no part of the claimed design.
